TRANSFER CAR

William Whaley, Knoxville, Tenn.

Application June 12, 1939, Serial No. 278,756

6 Claims. (Cl. 214—83)

This invention relates to an improvement in transfer cars for use in connection with loading machines to receive coal or other material and to transfer the same to a remote discharge point, or to direct the coal or other lading from the loading machine into mine cars at a stationary point.

This application is a continuation in part of my prior application on transfer cars, Serial No. 230,670, filed September 19, 1938.

In my prior application, a transfer car was provided containing a hopper with a conveyor in the bottom thereof terminating in an inclined section in one end of the car having a discharge section connected therewith and capable of raising and lowering to different parallel positions for directing the coal or other lading into a mine or other conveyor car.

Under some circumstances, particularly where the hopper of the transfer car is full, there is a tendency for some overflow of coal from the sides of the conveyor discharge section, or from the point where the conveyor leaves the body of the car to direct the lading rearwardly therefrom. Also, when the transfer car is full of coal, under some circumstances there is a tendency for the entire mass of coal to move simultaneously when the conveyor starts.

The object of this invention is to overcome this tendency and to insure a uniform flow of material through a restricted conveyor area, which is accomplished in this embodiment of this invention, by placing auxiliary plates in the bottom of the hopper, restricting the area of the conveyor exposed for part of the horizontal length of the hopper bottom. This provides for feeding the material onto the rear section of the conveyor in such a way as to fill this section completely and insure uniform discharge without spillage.

A preferred embodiment of this invention is illustrated in the accompanying drawings, in which:

Fig. 1 is a top plan view of this improved transfer car including this invention;

Fig. 2 is a side elevation thereof;

Fig. 3 is a vertical sectional view through a portion of the car body substantially on the line 3—3 of Fig. 1, parts being omitted for clearness; and

Fig. 4 is a similar view substantially on the line 4—4 of Fig. 2, with parts omitted.

This transfer car, in the form illustrated, is constructed with longitudinal members or side sills designated generally by the numeral 1, and

through which car axles 2 extend, having track wheels 3 fixed thereon adapted to travel on track rails 4, which may be the same rails on which the loading machine or mine cars travel. The transfer car is self-propelled, being driven by an electric motor 5, as illustrated, which operates sprocket gearing 6 to drive a counter-shaft 7, and the counter-shaft 7 operates through sprocket gearing 6 to drive one of the axles 2, the other axle being driven therefrom by sprocket gearing 9. This driving mechanism is conventional and any suitable means may be used as desired for driving the transfer car or transporting it from place to place. The side sills 1 carry bumpers 10 at opposite ends thereof.

The body of the car is generally of hopper shape and is supported upon the side sills 1, as shown more clearly in Figs. 3 and 4. Each of the side sills 1 has an angle bar 11 mounted on the top flange thereof, to which it is secured by welding, rivets, or otherwise and extending throughout a portion of the length of the side sills. Side walls 12 extend substantially lengthwise of the car with stiffening rim angle braces 13 at their upper edges and sloping lower sections 14 that extend downwardly to the upper edges of the angle bars 11 in the middle and forward portions of the car, as shown in Fig. 3, but in the inclined portion thereof, the sloping sides 14 extend substantially to the upper edges of supporting plates 15, extending upwardly from the side sills 1, as shown in Fig. 4. The side walls are suitably braced at intervals by angular brace plates 16. At the forward end 35 of the car the side walls 12 are connected together by an end wall 17, having a sloping lower portion 18.

At the rear portion of the car, the side plates 15 have secured thereto inclined plates 19 (Figs. 2 and 4), extending along the under edges of the inclined portions of the sloping sides 14 of the car body, and at the rearmost end of the plate 19 on each side of the car is a bracket plate 20 secured thereto. Pivotedly connected at 21 with each bracket plate 20 is one end of a lower link 22, while a second link 23 has one end pivotally connected at 24 with the bracket plate 20. The opposite ends of each pair of links 22, 23, are pivotally connected respectively at 25 and 26, with a bracket plate 27 secured at each side of a conveyor trough 28.

An endless conveyor is designated generally by the numeral 29 and extends from one end of the transfer car to the opposite end thereof, being preferably of the type designated as a flight

conveyor comprising a pair of chains 30 with flight bars 31 extending from side to side therebetween for raking the material over a trough plate 32 extending between the side sills 1 in the main portion of the car, being supported upon angle bars 33 (Figs. 3 and 4), which are secured to said side sills and to the side plates of the inclined portion of the conveyor structure. Each of the chains 30 has rollers 34 for guiding the same in trackways 35 at the upper run of the conveyor and upon tracks 36 for the lower run of the conveyor. The trackways 35 have tracks 36' therein, on which the rollers operate beneath angle plates 65 secured to the inner faces of the angle bars 11 in the forward portion of the car, and beneath angle bars 66 of the inclined portions of the conveyor.

The conveyor 29 has its chains 30 passing over sprocket wheels on a shaft 37 at the rearmost end of the car (Fig. 2) and over sprockets on a shaft 38 at the forward end of the car, the latter shaft being shown as driven through reduction gearing designated generally by the numeral 39 from an electric motor 40 under the control of the operator. If desired, this conveyor may be driven from the motor 5 by a driving connection therewith.

The controller for the motor 40 of the conveyor structure is designated generally by the numeral 41 and is mounted beside a platform 42 where an operator may be stationed for controlling the movements of the car. A similar controller 43 is mounted on the platform for controlling the electric motor 5 that operates the car forward and backward. A take up reel 44 may be provided on the car for winding of the electric cable thereon. The platform 42 is provided also with a seat 45 for the operator, if desired.

The discharge end portion of the conveyor structure is somewhat similar to that set forth in my prior patent on Conveyor for loading machines, No. 1,839,625, granted January 5, 1932, inasmuch as there is a discharge section of the conveyor that is maintained substantially in horizontal position by being supported upon parallel links, such as the links 22 and 23, pivotally connected respectively with the brackets 20 and 21 at opposite ends thereof, so that joint tilting movements of the links maintains them in parallel relation and moves the discharge section of the conveyor, having the conveyor trough 28, vertically to different parallel positions. To accomplish this raising and lowering movement of the discharge end portion of the conveyor, a bar 46 is connected between the links 22 and is pivotally connected intermediate its ends with a hydraulic power device 48 for raising the inclined section of the conveyor and for allowing the same to be lowered.

At opposite sides of the inclined tiltable section of the conveyor 29 are secured side plates 52, as shown in Fig. 2, being supported upon the links 22, while corresponding side plates 53 are secured to and extend along opposite sides of the trough 28, in order to increase the height of the trough through which the coal or other material is conveyed by the conveyor.

The sloping bottom of the hopper car body is so designed as to reduce the effective width of the conveyor for a part of its horizontal length, to insure uniform flow over the discharge end of the conveyor and to avoid spillage where the width and height of the hopper are reduced

leading toward the discharge of the conveyor therefrom.

This is accomplished by extending the angle plates 65 inwardly and appreciably over the lateral edges of the upper run of the conveyor, and mounting auxiliary plates 67 on the side wing positions 14 of the lading bottoms, which auxiliary plates 67 are secured to the sloping portions 14 as by rivets 68 at the outer edges thereof, from which they extend inward to the inner edges of the angle plates 65, to which they are joined at 69, thereby directing the coal toward the center of the bottom conveyor section at the forward end portion of the car, and materially reducing the effective width of the conveyor at the forward portion of its horizontal length to insure uniform flow over the discharge end of the conveyor, and to avoid spillage where the cross-section of the car hopper is reduced in width and height relative to the cross-section of the discharge part of the conveyor. This reduction in width will be apparent from Figs. 1 and 3, the full width of opening being shown in Fig. 4.

The operation of the transfer car will be obvious from the foregoing description. The transfer car is designed to operate behind the loading machine and to be filled directly therefrom, for which purpose the front wall 17 and forward portions of the side walls 12 are somewhat lower than the major portions of the side walls.

While the transfer car is in the room being loaded or is moving to or from the point of loading, the discharge end portion of the conveyor 29 is in its lowered position to facilitate travel in low head-room. After being loaded, the transfer car is caused to travel out of the entry at the room neck or other discharge point, being operated by its own power from the electric motor 5, and when it reaches this point, the hydraulic motor or power device 48 is actuated to lift the discharge end of the conveyor sufficiently high so as to clear the top of a mine car and project thereover and over the mine car track. Then the operator operates the conveyor whereby the lading is moved outward over the trough plate 32 and discharged at the rear end of the car directly into the mine car. The flight conveyor continues operating until all of the lading has been discharged from the transfer car or until the mine car is filled. Normally the capacity of the transfer car is about equal to two mine cars. After the transfer car is emptied, it is backed off from the mine car, the discharge end portion of its conveyor lowered, and then it is returned to the loading machine for refilling, such movements being self propelled and under the control of the operator.

In this way, the transfer car may be utilized for conveying the coal or other lading from the loading machine to a train of mine cars at the entry. The pivoted construction of the discharge end portion of the conveyor conserves head room in the mine while maintaining the discharge end always in a horizontal position when either raised or lowered.

While the foregoing describes the use of this car as a transfer car; under some conditions (such as ample head room) it may be found more valuable as a reservoir car used just back of the loading machine to receive material from the loading machine and to discharge same at a very rapid rate to each mine car as it is placed under the rear end of the transfer car conveyor.

Other uses of this unit will suggest itself to experienced mine operators.

It will be evident that this transfer car embodying this invention, may be mounted for ground operation on caterpillar or endless tread supports, or on resilient tire wheels, or other ground engaging wheels, and is not limited to operation on a track or on flange wheels.

The reference in the claims to "flow control means" or "flow control plates" is intended to designate such means or plates as will reduce the effective width of the conveyor exposed to the lading in the hopper for a part of its length, whereby the operation of the conveyor will move first the portion of the lading toward the discharge end and thereafter the remaining portion in the hopper, without a tendency for all of the lading to be moved upon the initial operation of the conveyor.

I claim:

1. In a transfer car, the combination of a frame having side sills, supporting wheels therefor, a car body mounted on the side sills and including side walls and one end wall with inclined lower portions sloping toward the center of the car, and an endless conveyor having a run underlying said sloping wall portions and extending throughout the major portion of the length of the car body and terminating in an inclined conveyor section at the end of the car body opposite the end wall and extending upwardly to a height approximately equal to the height of the side walls, and flow control means in the hopper body extending lengthwise thereof adjacent the inclined side wall portions and overlapping the conveyor.

2. In a transfer car, the combination of a supporting frame having side sills, supporting wheels therefor, a car body supported on the frame and having side walls and one end wall, said side walls having inclined lower portions extending inwardly approximately to the upright planes of the inner faces of the side sills, a trackway extending lengthwise of the car at the inner faces of the side sills, an endless conveyor having an upper run extending through said trackway below the inclined portion of the side walls in a position to receive material therefrom, and flow control means in the hopper body extending lengthwise thereof adjacent the inclined side wall portions and overlapping the conveyor.

3. In a transfer car, a car body having side walls and an end wall, said side walls having inclined lower portions for directing material toward the center of the car, a conveyor structure including a section extending approximately throughout the length of the car body underlying the inclined wall portions and forming the

bottom of the car, and flow control plates secured upon the inclined wall portions and overlying the edge portions of the conveyor section.

4. In a transfer car, a car body having side walls and an end wall, said side walls having inclined lower portions for directing material toward the center of the car, a conveyor structure including a section extending approximately throughout the length of the car body underlying the inclined wall portions and forming the bottom of the car, and flow control plates secured upon the inclined wall portions and extending inwardly from points adjacent the outer edges thereof in lateral overlying relation with the side portions of the conveyor section to direct the lading into the midportion of the conveyor section.

5. In a transfer car, a car body having side walls and an end wall, said side walls having inclined lower portions for directing material toward the center of the car, a conveyor structure including a section extending approximately throughout the length of the car body underlying the inclined wall portions and forming the bottom of the car, and flow control plates secured upon the inclined wall portions and extending inwardly therefrom in lateral overlying relation with the side portions of the conveyor section to direct the lading into the midportion of the conveyor section, said flow control plates extending from the forward end of the conveyor section lengthwise of the car toward the opposite end and terminating at a point spaced an appreciable distance from the last-mentioned end.

6. In a transfer car, the combination of a car body having side walls and one end wall, said walls having inclined lower portions for directing material toward the center of the car, an endless conveyor structure including a section extending approximately throughout the length of the car body underlying the inclined wall portions and forming the bottom of the car, means directing a portion of said bottom section upwardly in an inclined direction at the end of the car opposite the end wall to a height approximately corresponding with the height of the side walls whereby said inclined portion forms an end of the car, and flow control plates secured upon the inclined wall portions and extending inwardly therefrom in overlying relation with the side portions of the bottom conveyor section to direct the lading into the midportion thereof, said flow control plates extending from a point adjacent one end of the car toward the opposite end thereof and terminating approximately at the inclined portion of the conveyor.

WILLIAM WHALEY.
